CLAIM

The ornamental design for a slicer and grater storage container, as shown, and described.

DESCRIPTION

FIG. 1 is a perspective view of a slicer and grater storage container;

FIG. 2 is a left elevation view thereof;

FIG. 3 is a right elevation view thereof;

FIG. 4 is a front elevation view thereof;

FIG. 5 is a rear elevation view thereof;

FIG. 6 is a top view thereof; and,

FIG. 7 is a bottom view thereof.

The broken lines represent slicers and graters shown within the container, and the bottom gripping mat, form no part of the claimed design.
